UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

SHOCK ABSORBER FOR PAPER CARRIAGES.

Application filed October 10, 1921. Serial No. 506,701.

To all whom it may concern:

Be it known I, FRANK C. RINSCHE, a citizen of the United States, residing at Detroit, in the county of Wayne and State of Michigan, have invented certain new and useful Improvements in Shock Absorbers for Paper Carriages, of which the following is a specification.

My invention relates to tabulating means or equipments for adding machines and the like, and more particularly to that type of machine in which the paper carriage is propelled from one columnar position to another under the impulse of a motor, usually 10 a spring motor, the principal object of the invention being to provide improved cushioning mechanism for absorbing the shock or relieving the force of the impact of a tabulator dog or pawl on the carriage 15 against an arresting or stop member.

With the above and incidental objects in view, the invention consists in certain novel features of construction and combinations of parts, the essential elements whereof are recited in the appended claims, and the preferred form of embodiment of which is described in detail hereinafter and illustrated in full in accompanying drawings, which form part of this specification.

Of said drawings, Fig. 1 is a rear elevation of an adding machine with parts of the carriage and back plate broken away to disclose the construction, embodying the present invention, more clearly to view; Fig. 2 is a detail section on the line 2—2 of Fig. 1; Fig. 3 is a detail section through the carriage and the cushioning device, the section being taken on the line 3—3 of Fig. 1; Fig. 4 is a section through the dash pot 40 on the line 4—4 of Fig. 3, and Fig. 5 is a detail rear elevation of the cushioning device with the dash pot shown in section and the parts in the positions which they assume when a tabulating stop is disengaged from the yielding stop plate.

I am aware that the use of a dash pot as a cushioning device for a laterally shiftable paper carriage, and especially for such carriages on typewriting machines equipped 50 with tabulating mechanisms, is broadly not new, but such dash pots have only been used, so far as I know, to cushion or absorb the rebound or recoil shock of the carriage and parts, a spring being employed as the primary cushioning device to relieve the

shock when the tabulator stop on the carriage collides with an arresting or fixed stop. In such prior constructions, as generally exemplified by Patent No. 1,124,219, granted to C. T. Frantz, January 5, 1915, and Re-issue Patent No. 14,408, granted to C. T. Frantz, December 11, 1917, the carriage during a tabulating operation is moved towards the left past the predetermined columnar position by the inertia or momentum of the carriage and the cushion spring, which takes or absorbs the initial shock, stops the carriage at the end of its run, and then the carriage, due to energy stored up in the spring and the recoil of the carriage, is moved in the opposite direction and the dash pot is then called into play to cushion the rebound movement of the carriage. In these prior constructions the dash pots are mounted on and carried by the carriages.

In the present invention, the dash pot is associated with a sliding stop plate and both are mounted independently of the carriage on the frame of the machine and are so 80 constructed that the dash pot absorbs the shock due to the impact of a tabulator stop on the carriage against the sliding stop plate while the carriage is being moved directly to its predetermined position under the influence of the carriage spring drum, the parts being so proportioned and adjusted as to eliminate, as far as possible, any recoil or rebound of the carriage or parts. It will be apparent that very important advantages 85 are obtained by mounting the dash pot on the frame of the machine instead of on the carriage and by constructing the cushioning device as just explained, as no weight is added to nor change made in the carriage 90 and no time is lost due to vibration of the carriage, while at the same time the mechanism is extremely simple, highly efficient, practically noiseless, and readily adaptable to commercial machine now on the market 100 and in use, injury to the carriage parts is avoided, and accidental displacement of the adjustable tabulating stops on the carriage is obviated.

Referring now to the drawings, the reference numeral 10 designates generally the base plate or frame of the well known Burroughs adding machine and 11 the back plate or panel hinged to the base frame. Mounted on the back panel 11 is the custom- 110

ary carriage track 12 upon which the shiftable paper carriage 13 is adapted to run. A rock shaft 14 is mounted in the carriage and supports the usual tabulator or columnar stops or dogs 15, which are manually adjustable on the shaft 14 in a manner well understood in the art.

In lieu of the fixed or stationary stop, heretofore used in the Burroughs adding machine, is a yielding stop bar 17, having a shoulder 18 against which the columnar dogs 15 abut or collide to arrest the carriage in its predetermined columnar positions. The use of the fixed stop is objectionable as the impact of the tabulating stops on the carriage against it makes an objectionable noise and sometimes results in breakage of the carriage parts or displacement of the tabulator stops and the present invention overcomes these objections. As best shown in Fig. 2, the stop bar 17 is provided near its ends with inwardly extending (and preferably integral) spacing pillars or studs 19 which are reduced to form slide bearings 20 and still further reduced to form ends, which are screw threaded. The bearings 20 on the studs 19 are positioned in elongated slots 22 in the back panel 11 and the reduced screw threaded ends, which carry nuts on their outer ends, extend through apertures in a plate 23. The right hand stud 19 (as viewed in Figs. 1 and 2) is provided with wings or projections 24 which rest against the back panel 11 to hold the plates 17 and 23 in vertical planes and prevent any rocking vibration of these plates about the bearings 20, there being sufficient play between the plate 23 and the annular shoulders of the studs 19, contacting with the outer side of the back panel, to prevent binding or undue friction between the back panel and plate 23 or studs 19. One end of the plate 23 carries a stud 27 upon which is held by a headed screw a sliding bearing block 28 positioned in an elongated slot 29 in one arm of a yoked lever 30 which is pivoted on the back panel of the machine by a stud 31 projecting through a sleeve 26 which is fastened in the arms of the lever. The upper end of the other arm of the lever 30 is provided with a slot 32 in which is located a sliding bearing block 33 supported in the bifurcated end of a piston or plunger rod 34 by a bolt 35. The piston rod is carried by a piston or plunger 36 of the dash pot, the cylinder or casing 37 of the dash pot being supported on a bracket 38 secured to the back panel 11. The end or head of the cylinder is provided with a small hole 39 (Fig. 4), the passage of air therethrough being regulated by the adjustable screw 40, as will be explained presently. The lower end of the lever 30 is connected by a spring 42 to the frame of the machine, and this spring is preferably weaker or of

lesser tension than the spring of the spring drum 44 for propelling the carriage during tabulating operations, the spring drum being connected to the carriage by the usual tape 45.

As is customary in the Burroughs adding machine, a slide bar 47 (Fig. 1) is reciprocated vertically upon each operation of the machine through connections to the main rock shaft to elevate a pawl 48 which contacts with the particular tabulator stop 15 in engagement with the shoulder 18 on the stop plate 17, to disengage the same and permit the carriage to be moved to its next or selected columnar position by the spring drum 44.

From the above description, it will be obvious that when a columnar dog 15 is disengaged from the shoulder 18 of the stop plate 17 during an operation of the machine, the spring 42 rocks the lever 30 and thereby moves the piston 36 and the slide plates 18 and 23 to the positions shown in Fig. 5, this movement being limited by the engagement of the bearing portions 20 of the studs 19 against the ends of the slots 22. During the last increment of movement of the carriage to its next columnar or predetermined columnar position, under the influence of the spring drum, the proper stop 15 engages the shoulder 18 whereupon the stop plate 17, slide plate 23 and lever 30 are moved to the positions shown in Figs. 1 and 4, in opposition to the action of the spring 42 and the dash pot. The first effect or result of the impact of the tabulator stop with the shoulder on the stop plate 17 is to compress the air in the dash pot cylinder but this does not result in any rebound or recoil action of the carriage or the movable cushioning parts as the aperture 39 in the piston cylinder is sufficiently large to permit the air to escape from the cylinder thus counteracting or offsetting any tendency of the piston to rebound or recoil. As the air is compressed, it is gradually being expelled through the aperture 39 thereby gradually slowing up the movement of the carriage and finally arresting it in predetermined position, thus eliminating any back and forth vibration of the carriage. The piston 36 contacts without jar with the end of the cylinder of the dash pot (or it may engage with any other stationary part or member) when the carriage reaches its exact predetermined position and thus the dash pot acts to positively limit the movement of the stop plate and hence of the carriage toward the right (as viewed from the back), there being a slight clearance between the bearing portions 20 of the studs 19 and the ends of the slots 22 when the piston is in contact with the end of the cylinder, as clearly shown in Fig. 1.

As the tension of the spring 42 is less than

that of the spring drum, it will be manifest that the stop plate and the associated parts will be maintained in the position shown in Fig. 1 while the carriage is in stationary position and that, when the columnar stop 15 is rocked out of engagement with the shoulder on the stop plate 17, the spring 42 moves the stop plate and associated parts to the positions shown in Fig. 5. It will also be clear that the adjustable screw 40, which carries a lock nut 41, is provided to control the rate at which the air is dispelled from the dash pot, the space between the end of the screw and the end of the aperture 39 being increased or decreased according to the extent of cushioning effect required.

Fig. 5 has been described above as showing the condition of the cushioning device 20 after a tabular stop has been moved out of contact with the shoulder on the stop plate 17.

While the invention has been described as applied to the well-known Burroughs 25 adding machine, it is obvious that it may be applied to tabulating machines of other types and it is also to be understood that the embodiment of the invention described is susceptible of various modifications without departure from the scope and spirit of the invention, as defined in the appended 30 claims.

I claim:

1. In a machine of the class described, 35 the combination of a stationary frame, a laterally shiftable carriage, a motor for moving the same, a tabulator stop carried by the carriage, a stop member slidably mounted independently of said carriage on said frame and with which said tabulator stop is adapted to collide to slide the same, means for moving the tabulator stop into and out of cooperative alignment with said 40 slidable stop member, and a dash pot 45 mounted on said frame independently of said carriage and connected to said member to gradually stop the carriage during the last increment of movement of the carriage to its predetermined position by said 50 motor.

2. In a machine of the class described, the combination of a stationary frame, a carriage laterally shiftable thereon, a spring for moving the carriage, a tabulator stop 55 carried by the carriage, a stop member slidably mounted on said frame independently of said carriage and with which the tabulator stop is adapted to collide to slide the same, means for moving said tabulator stop into and out of operative alignment with 60 said slidable stop member, and a dash pot connected to said member and mounted on said frame.

3. In a machine of the class described, 65 the combination of a stationary frame, a

carriage laterally shiftable thereon, a spring for moving the carriage, a tabulator stop carried by the carriage, a stop member slidably mounted on said frame independently of said carriage and with which the tabulator stop is adapted to collide to slide the same, means for moving said tabulator stop into and out of cooperative alignment with said 70 slidable stop member, and a dash pot, comprising a piston and a cylinder, connected to said member and mounted on said frame, and positively arresting the carriage by engagement of the piston with the end of the cylinder.

4. In a machine of the class described, the combination of a stationary frame, a carriage laterally shiftable thereon, a spring for moving the carriage, a tabulator stop carried by the carriage, a stop plate slidably mounted on said frame independently of said carriage and with which the tabulator stop is adapted to collide to slide the same, means for moving said tabulator stop into and out of cooperative alignment with said 80 slidable stop member, a dash pot connected to said stop plate and mounted on said frame, and an adjustable device for controlling an opening in said cylinder and thereby regulating the cushioning effect of 85 said dash pot.

5. In a machine of the class described, the combination of a frame, a laterally shiftable carriage, a spring for shifting the carriage, a tabulator stop associated with the carriage, a sliding bar mounted on said frame and adapted to be engaged and slid by said tabulator stop to arrest the carriage in predetermined position, means for moving said tabulator stop into and out of cooperative alignment with said sliding bar, a dash pot 90 mounted on said frame and comprising a piston and a cylinder, one of said elements of the dash pot being connected to said bar and moved in one direction to relieve the impact of the stop against the bar, and a 95 spring for moving the last mentioned element of the dash pot in the opposite direction.

6. In a machine of the class described, the combination of a frame, a laterally shiftable carriage, a spring for shifting the carriage, a tabulator stop associated with the carriage, a sliding bar mounted on said frame and cooperating with said tabulator stop to arrest the carriage in predetermined position, a lever pivoted to said frame, a dash pot mounted on said frame and comprising a piston and a cylinder, one of which elements is connected to said lever and which is moved in one direction to relieve the impact of the stop against the bar, and a spring connected to said lever for moving the element of the dash pot connected thereto in the opposite direction.

7. In a machine of the class described,

- the combination of a laterally shiftable carriage, tabulator stop mechanism therefor comprising cooperating parts, a dash-pot, comprising a cylinder and piston, associated with said stop mechanism to act as a cushion for said carriage, and an operating connection between one of said elements of said dash-pot and one of said parts of said tabulator stop mechanism, for causing said element of the dash-pot to move substantially further than said part while the carriage is being arrested.
8. In a machine of the class described, the combination of a laterally shiftable carriage, tabulator stop mechanism therefor comprising a stop on the carriage and a stop with which the first stop collides, a dash-pot comprising a piston and a cylinder, and a lever associated at one end with one of said stops and at the other end with one of said dash-pot elements and pivoted so that the element with which it is associated moves substantially further than the stop with which it is associated while the carriage is being arrested.
9. In a machine of the class described, the combination of a laterally shiftable carriage, tabulating stop mechanism therefor comprising coacting stops of which is slidable, a dash-pot comprising a piston and a cylinder, an operating connection between one of said elements of said dash-pot and said slidable stop so that when the stops collide the element to which the connection is associated moves substantially further than the slidable stop to gradually stop the carriage during the last increment of movement of the carriage to its predetermined position, a spring for sliding the stop in the opposite direction when the stops are disengaged, and means for disengaging the stops.
10. In a machine of the class described, the combination of a laterally shiftable carriage, tabulator stop mechanism comprising coacting parts one of which is slidable, a cushioning device for the carriage, a lever connected at one end to said slidable stop and at its opposite end to said cushioning device and pivotally mounted nearer its connection with the slidable stop than with the cushioning device, so that the latter moves further than the former to gradually stop the carriage during the last increment of movement of the carriage to its predetermined position.
11. In a machine of the class described, the combination of a rear frame, a laterally shiftable carriage, a spring for shifting the carriage, a tabular stop associated with the carriage, a cushioning device mounted on the inside of the frame, a slidable member connected to said device, and a stop on the outside of said frame, carried by said member and adapted to be engaged by said tabulator stop to arrest the carriage.
12. In a machine of the class described, the combination of a rear frame, a laterally shiftable carriage, a spring for shifting the carriage, a tabulator stop associated with the carriage, a cushioning device mounted on the inside of the frame, a slidable member connected to said device, a stop element on the outside of said frame, carried by said member and adapted to be engaged by said tabulator stop to arrest the carriage, and means between the frame and stop element for effecting disengagement of the latter from the tabulator stop.
13. In a machine of the class described, the combination of a laterally shiftable carriage, tabulator stop mechanism therefor comprising cooperating stops, an air dash-pot, comprising a piston and a cylinder from which the air is dissipated associated with said stop mechanism to act as a cushion for said carriage, and an operating connection, including a lever between one of said elements of said dash-pot and one of said stops of said tabulator stop mechanism, the lever being pivoted so that said element of the dash-pot moves substantially further than said stop while the carriage is being arrested.

FRANK C. RINSCHE.
